HEEL-SEAT FITTING MACHINE

John William Pratt, Leicester, England, assignor to United Shoe Machinery Corporation, Borough of Flemington, N. J., a corporation of New Jersey

Application June 21, 1938, Serial No. 214,917
In Great Britain June 30, 1937

16 Claims. (Cl. 12—31.5)

This invention relates to machines for use in the manufacture of shoes and is illustrated as embodied in a machine for reducing the heel-seat portions of soles for the reception of heels.

5 It is an object of the present invention to improve machines of the general type disclosed in United States Letters Patent No. 1,980,369, granted November 13, 1934, on an application filed in the name of Frank Barton to adapt them 10 for forming upon unattached soles of shoes heel-seat tabs which substantially fill the cupped attaching faces of heels of shoes to which the soles are attached.

15 The various features of the invention will be understood and appreciated from the following detailed description read in connection with the accompanying drawings, in which

Fig. 1 is a front view, partly broken away, of the illustrated machine;

20 Fig. 2 is a side view, partly broken away, of the forward portion of the machine;

Fig. 3 is a vertical section of the front portion of the machine on line III—III of Fig. 1;

25 Fig. 4 is a view, partly broken away, of the forward portion of the machine on line IV—IV of Fig. 3;

Fig. 5 is a detail view showing in perspective mechanism for bending and clamping the heel-seat portion of the sole preparatory to reducing 30 the same in the manner illustrated in Fig. 10;

Fig. 6 is a perspective view, partly in section on line VI—VI of Fig. 3, showing the heel-seat portion of the sole being reduced by the machine;

35 Fig. 7 is an enlarged sectional view on line VII—VII of Fig. 6;

Fig. 8 is an exploded view of parts constituting a bulger unit used when it is desired to reduce the sole in the manner illustrated in Fig. 10;

40 Fig. 9 is a view similar to Fig. 5 showing mechanism for bending and clamping the heel-seat portion of the sole preparatory to reducing the same in the manner illustrated in Fig. 11;

45 Fig. 10 is a perspective view of the heel-seat portion of a sole after it has been reduced by the machine illustrated in Figs. 1 to 8, inclusive;

Fig. 11 is a perspective view showing the heel-seat portion of a sole after it has been operated 50 upon by the machine equipped with the sole-bending and clamping mechanism illustrated in Fig. 9;

Fig. 12 is a perspective view of a modified bulger which may be substituted for the bulger 55 shown in Fig. 8; and

Fig. 13 shows a modified presser roll which is used in conjunction with the bulger of Fig. 12.

The illustrated machine comprises a matrix plate 20 having a U-shaped opening 22 (Figs. 4 and 5) through which the central part of the heel-seat portion 24 (Figs. 6 and 7) of a sole 26 (Fig. 10) is forced by a bulger 28 of a bulger unit 30 (Fig. 8) after the side margins of the heel-seat portion of the sole have been forced by clamps 32 against a beveled face 34 of the matrix plate 20. After the heel-seat portion of the sole has been bent and clamped as above described it is reduced upon forward movement of a knife 36 (Figs. 1, 2, 3 and 6), which has a straight cutting edge 38 (Fig. 6) in contact with the flat upper face 40 of the matrix plate 20, to form a heel-seat tab 42 (Fig. 10). It will be noted that a U-shaped piece 44 of surplus material trimmed from the heel-seat portion 24 (Figs. 6 and 7) of the sole 26 is left secured to the sole until after the sole has been attached to the shoe, in accordance with the practice disclosed in United States Letters Patent No. 1,708,962, granted April 16, 1929, on an application filed in the name of Barclay et al.

At each side of the main frame 46 of the machine are ledges 48 (Figs. 1 and 3) upon which the matrix plate 20 is supported, upwardly extending walls 50 (Fig. 1) serving to prevent lateral movement of the matrix plate. The rear portion of the matrix plate 20 is provided with laterally extending shoulders provided with recessed portions 52 (Fig. 4) which engage vertical bolts 54 (Figs. 2 and 4) fitting in bores in the main frame 46, to limit rearward movement of the matrix plate 20 along the ledges 48. Each bolt 54 has a head 56 which engages a counter-bored portion of the matrix plate, the arrangement being such that the upper surface of the head 56 is at all times below the upper face 40 of the matrix plate 20.

Extending inward from the opposite sides of the matrix plate 20 near its forward end are slots 58 (Figs. 1 and 4). Bolts 60 are arranged to enter the respective slots 58, and heads of the bolts 45 are clamped, through mechanism which will appear later, against the upper face 40 of the plate to force the matrix plate 20 against the ledges 48 (Figs. 1 and 3). Each bolt 60 extends downward through a slot 62 (Figs. 1 and 4) in the main frame 46, the slots 62 being large enough to insure that the bolts 60 may be moved out of the slots 58 of the matrix plate 20 in order to enable the operator to move the matrix plate forward out of the machine preparatory to plac-

ing another matrix plate which has a different shaped opening 22 in the machine. The lower end of each bolt 54 (Fig. 2) is threaded into a horizontal stud 64 and is locked to the stud by a set screw 66. Similarly the lower end of each bolt 60 (Figs. 1 and 2) is threaded into a horizontal stud 68 and is secured thereto by a set screw 70. The studs 64 and 68 at each side of the machine are mounted in bores at the rear and forward ends respectively of a lever 72 (Figs. 1, 2 and 4). The studs 64 and 68 are rotatable in the bores, elongated slots 74 (Fig. 2) and 76 (Figs. 1 and 2) being formed in the lever through which slots the respective bolts 54 and 60 pass. The levers 72 extend forward and rearward of the machine, each lever normally lying below the corresponding ledge 48. Threaded into each of the levers 72 is a screw 78 (Figs. 1, 2 and 4) the upper end of which is arranged to engage the main frame 46. Each screw 78 has pinned to it an outwardly extending arm 80 through which the screw is rotated. The screw 78 at the right side of the machine (Fig. 1) has a left-hand thread and the screw at the left side of the machine has a right-hand thread. Accordingly, when the arms 80 are swung forward the screws 78 are rotated in the respective levers 72 which are moved bodily downward causing the bolts 54 and 60 to clamp the matrix plate 20 in position against the ledges 48.

When it is desired to remove the matrix plate 20 from the machine, the arms 80 are swung rearward with relation to the levers 72 to slacken the bolts 54, 60. When the arms 80 contact lugs 82 (Figs. 2 and 4) of the respective levers 72, further rotation of the screws 78 with relation to the levers 72 is prevented, continued rearward pressure of the arms 80 causing the front ends of the levers and the bolts 60 to move outward about the axes of corresponding bolts 54 until the bolts engage the outer walls 84 (Fig. 1) of the slots 62.

The bolts 60 are therefore moved out of the slots 58 in the matrix plate 20 so that the operator can move the matrix plate from the machine. Another matrix plate having a U-shaped opening 22 of a different size is then placed on the ledges 48 and moved rearward until it engages the bolts 54. The arms 80 are then swung forward. Lock washers 86 (Fig. 2) arranged between the corresponding arms 80 and levers 72 tend to resist rotary motion of the screws 78 in the levers 72 to insure that during the first part of the forward movement of the arms the front ends of the levers and the bolts 60 shall move inward into the slots 58. Continued forward movement of the arms 80 rotates the screws 78 in the levers 72 forcing the levers downward and thereby causing the bolts 54 and 60 to clamp the matrix plate 20 against the ledges 48. When the arms 80 are moved rearward in the manner above described the releasing of the heads of the bolts 54 and 60 from the matrix plate 20 is insured through the provision of spring-pressed plungers 88 (Fig. 2) which are housed in bores of the levers 72 and engage portions of the respective bolts 54 projecting below the studs 64. It will be appreciated that when allowed to do so the plungers 88 serve to move the forward ends 70 of the levers 72 upward.

With the above construction and arrangement of the matrix plate 20 and associated parts the matrix plate may be quickly removed and replaced by another plate having a U-shaped opening of a different size or shape. In a run of

shoes of the same style it is customary to use three or more matrix plates having U-shaped openings of different sizes in accordance with the desired size of tab to be formed at the heel end of the sole.

The bulger unit 30 (Fig. 8) is usually replaced by another unit having a bulger 28 of a different size or shape whenever the matrix plate 20 is replaced by another. The size of the bulger 28 used depends also to some extent upon the thickness of the sole being operated upon. The bulger unit 30 is removably mounted upon the upper end of a slide 90 (Figs. 3 and 6) vertically movable in a sleeve or slide 92 which is vertically movable in a bore 94 (Figs. 2 and 3) of the main frame 46. The sleeve 92 is supported by a collar 96 on a rod 98 threaded into the lower end of the slide 90. A compression spring 100 (Figs. 1, 2 and 3) surrounds the rod 98 and bears at its upper end against the collar 96 (Figs. 2 and 3) and at its lower end against a hand wheel 102 (Fig. 2) threaded onto the rod. The spring 100 urges the sleeve 92 upward with relation to the slide 90 and when the machine is idle a shoulder 104 (Fig. 3) at the upper portion of the sleeve 92 is held in contact with a cooperating shoulder on the slide 90. Secured by screws 106 (Figs. 1 and 6) to the upper end of the sleeve 92 are a pair of horizontal lugs 108 which serve as supports for the clamps 32, as will be described later. The bulger 28 and the clamps 32, together with the slide 90 and the sleeve 92 through which the respective bulger and clamp are operated, may be referred to as a plunger unit.

The upper end of the slide 90 is provided with a guideway 110 (Figs. 1 and 6) for receiving a block 112 comprising part of the replaceable bulger unit 30 (Fig. 8). Formed in the slide 90 below the guideway 110 is a slot 114 (Figs. 3 and 6) for receiving a latch 116 which is pivoted on a pin 118 secured to the slide 90 and is constantly urged upward by a spring-pressed plunger 120 (Fig. 3). The block 112 is positioned in the guideway 110 by a shoulder 122 (Fig. 3) of the sleeve 92 and is held upon the slide 90 by the latch 116.

The bulger unit 30 (Fig. 8) comprises the bulger 28, the block 112, and a sole gage 124. The block 112 and the bulger 28 are clamped together by two screws 126 (Fig. 3) the bulger having depending flanges 128 (Figs. 6, 7 and 8) which engage upper surfaces of the block 112. Formed between the block 112 and the bulger 28 is a recess for receiving the shank of the sole gage 124 which is normally held in its operative position by a screw 130 (Fig. 3) passing through a countersunk slot 132 (Figs. 3 and 8) of the gage and threaded into the block 112. A recess 134 in the bulger 28 provides access to the screw 130. After the screw 130 has been loosened the sole gage 124 is adjusted to its proper position with respect to the bulger 28 and the gage is then locked in its new position by setting up the screw. The work-engaging portion of the sole gage 124 is curved upward from its shank. It will be noted (Figs. 3 and 5) that the upper face 136 of the sole gage 124 is approximately at the same level as a flat ridge 140 (Figs. 3, 4, 5 and 8) of the bulger 28, the forward face of the gage 124 being inclined forward and upward to form a lip. When the sole 26 from which a heel-breast covering flap 142 (Fig. 10) has been split is positioned in the machine the flap is turned downward, the lip of the gage 124 engaging the sole 75

at the junction of the body portion of the sole and the split flap. The gage 142 may be adjusted from time to time to insure that when the sole is positioned in the machine as above described, the heel-seat portion 24 thereof shall be located accurately in the machine.

The sole-engaging portion of the bulger 28 is narrowest (Figs. 4, 5 and 8) at its forward end portion from whence it gradually increases in width until it ends in a rounded rear end portion. It will be noted (Fig. 4) that the bulger 28 has a U-shaped outline considerably smaller than the U-shaped opening 22 of the matrix plate 20. In order to form the tab 42 (Fig. 10) which is of a preferred outline and has a wide beveled margin 144, the sole-engaging portion of the bulger 28 is constructed as best shown in Figs. 5 and 8, and a presser roll 146 is provided for progressively forcing the heel-seat portion 24 of the sole against the bulger immediately ahead of the knife 36 thereby insuring that the sole shall be conformed to the upper face of the bulger and preventing the central part of the heel-seat portion of the sole from being sucked or drawn away from the bulger 28 as the knife 36 forms the tab 42. The upper margin of the bulger 28 is rounded off along its sides and around its rear end portion, the degree of bevel at the rear end portion being greater than the degree of bevel along the sides. The sole-engaging portion of the bulger 28 comprises the flat central ridge 140 and a pair of beveled lateral margins 148 (Figs. 4, 5 and 8) inclined to the ridge. At the rear end of the ridge 140 is a portion 150 (Fig. 8) which is spaced by shoulders 152 (Fig. 8) from the lateral margins 148 of the bulger.

When the bulger 28 is moved to its raised position (Figs. 6 and 7) to press the heel-seat portion 24 of the sole through the U-shaped opening 22 of the matrix plate 20, the ridge 140 is approximately in alignment with the upper face 40 of the matrix plate. Accordingly, the central portion 154 (Fig. 10) of the tab 42 formed upon the sole is of a thickness equal to the full thickness of the sole and the lateral margins 144 of the tab 42 are beveled. By beveling off the rear end of the bulger 28 as above described it has been found that the rear end of the tab 42 is trimmed on a long bevel which merges attractively with the beveled lateral margins 144 of the tab.

The knife 36 is secured by a screw 156 (Fig. 3) and a clamp plate 158 to a carrier 160 which reciprocates forward and rearward along a guideway (not shown) of the machine frame 46. The knife carrier 160 is similar to the knife carrier disclosed in the above-mentioned United States Letters Patent No. 1,930,369 and is operated upon tripping a one-revolution clutch (not shown).

The presser roll 146 and the mechanism for operating the same will now be described. Extending from a bracket 162 (Figs. 1, 2 and 3) which is secured to the knife carrier 160 is a horizontal pin 164 upon which is pivoted a block 166. The block 166 is normally held in the position illustrated in Figs. 1, 2 and 3 with relation to the bracket 162 and is prevented from turning in a clockwise direction (Figs. 2 and 3) about the pin 164 by engagement with an extension 168 of the bracket. The block 166 is normally prevented from turning in a counterclockwise direction by a latch 170 (Figs. 1 and 2) which is pivoted on a screw 172 secured to the block 166 and has a hook-shaped end (Fig. 2) normally embracing a pin 174 secured to the bracket 162. A tension

spring 176 holds the latch 170 in engagement with the pin 174. The latch 170 has an upward extending portion which may be moved rearward by the operator to lower the hook-shaped end of the latch away from the pin 174. When the block 166 has been swung upward about the pin 164, for purposes which will appear later, movement of the latch 170 under the action of the spring 176 is prevented by a stop pin 178 projecting from the block 166.

The block 166 has a vertical bore 180 (Fig. 3) in which moves a slide 182 having a rod 184 projecting therefrom. A screw 186 (Figs. 1 and 2) is threaded into the upper end of the block 166 and has a bore through which the rod 184 passes. Surrounding the rod 184 and located between the screw 186 and the slide 182 is a compression spring 188. Extending downward from the slide are two arms 190 for supporting a horizontal pin 192 which is threaded into one of the arms and on which the presser roll 146 is rotatably mounted. The arrangement is such that the presser roll 146 is located immediately in advance of the cutting edge 38 of the knife 36 and travels ahead of the knife during its cutting stroke. When the knife 36 is retracted (Fig. 3) the presser roll 146 engages the upper face 40 (Figs. 5 and 6) of the matrix plate 20 just rearward of the U-shaped opening 22. As the knife 36 advances the presser roll 146 travels forward on the upper surface of the sole which is forced upward through the U-shaped opening 22 by the bulger 28 and portions of the clamps 32 and serves to press the sole firmly into contact with the bulger and to hold it against being sucked up by the knife. The amount of pressure exerted against the sole by the presser roll 146 is controlled by the degree of compression of the spring 188 which may be varied by turning the screw 186. To prevent the slide 182 from being moved too far downward by the spring 188 should the machine be operated with no work therein the slide has a slot 194 (Fig. 3) in which is received a pin 196 secured in the block 166.

The presser roll 146 comprises two frusto-conical portions 198 (Figs. 1 and 7) which are spaced by and taper toward a circumferential groove 200 slightly wider than the ridge 140 of the bulger 28. As the presser roll 146 advances during the operation of the machine it bends the central part of the heel-seat portion 24 of the sole transversely to a shape complementary to the widthwise curvature of the upper face of the bulger 28, and as the knife 36 makes its cut the sole is maintained in this shape and is not permitted to be sucked or drawn away from the upper surface of the bulging member under the action of the knife.

The slide 90 through which the clamps 32 and the bulger 28 are moved to and from their raised operative positions (Figs. 6 and 7) is operated by a lever 202 (Fig. 3) pivoted upon a bearing pin 204 secured to the main frame 46. The front end of the lever passes through a slot 206 in the sleeve 92 and is provided with a knob 208 fitting in a recess 210 of the slide. The mechanism for operating the lever 202 comprises a treadle rod (not shown) which is depressed by the operator to raise the slide 90 until the ridge 140 of the bulger 28 is level with the upper face 40 of the matrix plate 20, movement of the lever 202 in a counterclockwise direction, as viewed in Fig. 3, being limited by an adjustable stop (not shown). After the heel-seat portion of the sole has been bent to the proper shape between the matrix plate 20 on the one hand and the clamps 32 and the bulger

28 on the other hand (Figs. 6 and 7) the operator continues to depress the treadle thereby tripping the above-mentioned one-revolution clutch (not shown) to operate the tab-forming knife 36.

5 Since the mechanism for operating the lever 202 and tripping the clutch is substantially identical with mechanism disclosed in the above-mentioned United States Letters Patent No. 1,980,369, it will not be necessary further to describe such mechanism herein.

Should it happen in the operation of the machine that the knife 36 only partly completes its tab-forming stroke and it is therefore desirable again to operate upon the sole, the roll 146 in its 15 second advance may tend to carry in front of it the partly formed tab, thus interfering with the formation of a properly formed tab. Accordingly, in order to avoid such an occurrence, the block 166 is so mounted upon the bracket 162 that it may

20 be swung to an inoperative position with respect to the bracket. When the knife 36 only partially completes its forward tab-cutting stroke the operator releases the latch 170 and swings the block 166 upon the pin 164 to move the roll 146 upward to its inoperative position away from the matrix plate 20. A leaf spring 212 is secured by a screw 214 to the bracket 162 and when the block 166 is swung to its raised inoperative position the leaf spring engages a surface 216 of the block to maintain the same in its raised position. The machine can be again operated with the roll 146 in its inoperative position thereby avoiding the above-mentioned undesirable effect.

25 After the machine has come to rest the operator then lowers the block 166 and the parts carried thereby to their operative positions illustrated in Figs. 1, 2 and 3.

The clamps 32 of the illustrated machine will 30 now be described in detail. The two lugs 103 which extend horizontally rearward from the upper end of the sleeve 92 serve as supports for clamp-carrying arms 218 which are pivoted through the provision of pivot studs 220 to the corresponding bars 108. Each of the clamps 32 35 comprises a detachable block or section 222 (Figs. 1, 4 and 5) which is supported by a corresponding lug 108 and which is mounted upon a pin 224 projecting from the forward end of the arm 218 and is held in place on the pin by a spring 226. 40 Projecting inner faces 228 (Figs. 6 and 7) of the clamps 32 engage the outer sides of the bulger 28, a tension spring 230 (Figs. 3, 4 and 5), opposite ends of which are secured to studs 232 carried by the respective arms 218, serving to maintain the clamps 32 in abutting relation with the bulger 28. The lower portions of the inner faces of the clamps 32 are cut away as indicated at 234 (Figs. 6 and 7) in order to insure that only the faces 228 of the clamps shall engage the bulger 28. 45 Upstanding pins 236 (Figs. 3 and 4) projecting from the bars 108 serve when the bulger 28 has been removed from the slide 90 to limit inward movement of the clamps 32 under the action of the spring 230 thereby facilitating the insertion of the bulger 28 between the clamps.

The pivot studs 220 are spaced a considerable distance apart and are positioned about five inches rearward of the clamps 32 to insure that during the slight degree of pivotal movement of the arms 70 218 which takes place when the clamps 32 adjust themselves to bulgers 28 of different sizes, the angular positions of the clamps shall not be altered to any appreciable degree. The axes of the pivot studs 220 may be described as being disposed at right angles to the upper face 40 of

the matrix plate 20 and positioned substantial distances rearward of the U-shaped opening 22.

When the machine is idle sole-penetrating teeth 238, which may be referred to as extensions of the clamps 32, are arranged above the level of the ridge 140 of the bulger 28. During the first part of the upward movement of the bulger 28 caused by the upward movement of the slide 90, the sleeve 92 carrying the lugs 108 is raised by the spring 100 carried by the slide 90 causing the 10 clamps 32 to force the side margins of the heel-seat portion of the sole against the beveled face 34 of the matrix plate 20. The slide 90 is permitted to move upward independently of the sleeve 92 until the ridge 140 of the bulger 28 has been raised to the level of the upper face 40 of the matrix plate 20 causing the central part of the heel-seat portion of the sole to be raised above said upper face.

15 It will be understood that the same pair of clamps 32, including the blocks 222, can usually be used satisfactorily in conjunction with different sized bulgers 28 when the U-shaped portion 44 of surplus surface material is to be left attached to the sole as shown in Fig. 10. A shorter pair of clamps 240 (Fig. 9), preferably the clamps 32 illustrated in Fig. 5 with the blocks 222 removed, are used with corresponding bulgers 242 when it is desired, as will later appear, to remove a U-shaped chip 244 (Fig. 11) of surplus material from the sole by a cut which forms a tab 245 and shoulders 246.

20 It is customary to change the clamps 32 as well as the bulgers 28 and the matrix plates 20 when changing from the production of work in which the U-shaped portion 44 is to be left attached to the sole, to the production of work in which the U-shaped portion 244 (Fig. 11) is to be completely severed from the sole or vice versa. Accordingly, the clamps 32 comprise the above-described 25 blocks 222 which may be readily removed from the machine to provide the shorter clamps 240 shown in Fig. 9. As will later appear, the clamps 32 may be used without the blocks 222 in conjunction with the bulger 242 to provide the sole illustrated 30 in Fig. 11, or may be used with the blocks in conjunction with the bulger 28 illustrated in Figs. 5 and 8 to produce the sole illustrated in Fig. 10.

35 The curvature of the side portions of different bulgers engaged by the clamps does not vary substantially and accordingly the same clamps may be effectively used with different bulgers. The illustrated machine is not provided with a separate clamp for forcing the rear end of the heel-seat portion 24 of the sole against the beveled face 34 of the matrix plate 20 since it has been found that satisfactory results are obtained without use of such a clamp.

40 It will be noted that when the bulger 28 is in its raised operative position shown in Fig. 7 it is spaced a considerable distance, preferably about $\frac{1}{16}$ of an inch, inward from an edge 247 formed by the intersection of the flat face 40 and the beveled face 34 of the matrix plate 20. Accordingly a gap 248 through which the heel-seat portion 24 of the sole passes is formed between the raised bulger 28 and the edge 247 of the matrix plate 20. At each side of the U-shaped opening 22 the gap 248 is filled to a considerable extent by the teeth 238 of clamps 32, which teeth extend slightly above adjacent areas of the lateral margins 148 of the sole-engaging portion of the bulger 28. Thus when the bulger 28 and the clamps 32 are in their raised operative positions (Figs. 6 and 7) the clamps not only force op- 45

posite side margins of the heel-seat portion 24 of the sole against the beveled face 34 of the matrix plate 20 along the sides of the opening but also force portions of the sole in the vicinity 5 of the gap 248 above the face 40 of the matrix plate and with considerable pressure against the edge 247 of the plate.

With the above-described construction in which the bulger 28 is considerably smaller than 10 the U-shaped opening 22 and has its ridge 140 moved upward to the level of the face 40 of the matrix plate 20 regardless of the thickness of the sole, and in which the teeth 238 of the clamps 23 effectively force portions of the sole in the vicinity 15 of the gap 248 against the edge 247 of the matrix plate, the sole is bent slightly around the edge 247, as shown in Fig. 7, with the result that the tab 42 formed by the knife 36 is of substantially the same width as the U-shaped opening, 20 and has a central portion 154 of the full thickness of the sole and a wide beveled margin 144. The teeth 238 are sharp enough to penetrate to a slight extent the portion of the sole passing through the gap 248 thereby securing the sole 25 against lengthwise displacement under the action of the heel-seat reducing knife 36.

As above explained, the U-shaped portion 44 (Fig. 10) of surplus material left after forming the heel-seat tab 42 by the machine illustrated 30 in Figs. 1 to 8, inclusive, is attached at its forward end to the sole. The operator usually severs the U-shaped portion 44 from the sole while forming heel-breast receiving shoulders (not shown) on the sole after the attachment of the sole to the 35 shoe.

In the manufacture of shoes having Louis heels it is common practice to reduce the heel-seat portion of the unattached sole by a single incision in the manner illustrated in Fig. 11, the resultant 40 tab 245 being slightly shorter than the tab 42 and the shoulders 246 being constructed and arranged to be engaged by the forward portion of the attaching face of a heel after the sole has been attached to the shoe. In order to equip 45 the illustrated machine for trimming the sole just described the bulger 242 (Fig. 9) is substituted for the bulger 28 and the blocks 222 are removed from the clamp 32. The bulger 242 comprises a laterally extending bar 250, the upper 50 face of which lies in a plane of a flat ridge 252 of the shank portion 253 of the bulger 242 which is shorter than the bulger 28, but otherwise is of the same shape as the bulger 28. The bulger 242 is secured by screws (not shown) to the block 112 and to the gage 124 to provide the bulger unit 55 shown in Fig. 9 which corresponds to the above-described bulger unit 30 shown in Fig. 8.

A matrix plate 254 (Fig. 9) used in conjunction with the bulger 242 is cut away at its front portion to provide clearance for the bar 250 and 60 has a U-shaped opening 256 which is shorter than the opening 22 of the matrix plate 20 to accommodate the shank portion 253 of the bulger 242. The rear portions of the bar 250 are beveled, as 65 indicated at 258 and are arranged just ahead of the front edges 260 of the matrix plate 254 when the sole is clamped in the machine. When in the operation of the machine the bulger 242 is raised the portion of the sole lying just in front 70 of the front edges 260 of the matrix plate 254 is raised above the level of the upper face 261 of the matrix plate so that the knife 36 during its advance, severs the U-shaped portion of surplus material 244 from the sole by cutting through 75 the margins of the sole at each side thereof to

form the shoulders 246. It will be understood that when tabs 245 (Fig. 11) of different sizes and shapes have to be produced the unit formed by the bulger 242, the block 112, and, if desirable, the sole gage 124 may be readily interchanged for 5 another unit in which the bulger is of a different size or shape. Moreover, a corresponding change of matrix plate 254 may be quickly effected as above described.

In order to centralize soles in the machine 10 there is provided a bifurcated work gage 262 which is located just below the matrix plate 20 at the rear end of the U-shaped opening 22. The work gage 262 is normally urged forward by a spring (not shown) and may be moved rearward under pressure of the sole. In operating upon soles which do not have breast flaps 142 the gage 124 is removed from the machine and the sole is positioned lengthwise and widthwise by forcing the same against the gage 262 which 15 yields rearward until its movement is limited by an adjustable stop (not shown). When the machine is equipped with the bulger 242 (Fig. 9), the matrix plate 254 and the clamps 240 to reduce the heel-seat portion of the sole in the manner 20 shown in Fig. 11, the U-shaped chip 244 trimmed from the sole has to be removed from the top of the matrix plate 254. In order to eject the U-shaped chip 244 from the machine the work gage 262 is moved rapidly by a spring (not shown) to 30 its forward inoperative position after the bulger 242 has been lowered, thereby forcing the chip from the machine. The work gage 262 and the mechanism for causing the same to eject the U-shaped chip 244 from the machine is fully disclosed in the above-mentioned United States Letters Patent No. 1,980,369 and need not be further described herein.

It may be desirable when the sole is thick and stiff, for example, to substitute a bulger 264 (Fig. 40 40) for the bulger 28. The bulger 264 has a sole-engaging portion comprising a flat upper ridge 266 which is raised about $\frac{1}{2}$ of an inch above lateral margins 268 of the sole-engaging portion of the bulger, which lateral margins are 45 rounded upward adjacent to the ridge 266 and downward where they blend with the side faces of the bulger. The ridge 266 of the bulger 264 is of uniform width and terminates a considerable distance from the rear end of the bulger. 50 The rear part 270 of the sole-engaging portion of the bulger 264 curves away gradually toward its rear end and sides, the arrangement being such that the outer rim 278 of the sole-engaging portion of the bulger lies in approximately the same 55 plane. The rear part 270 of the sole-engaging portion of the bulger 264 may be described as being of somewhat spherical shape, the highest part of which is substantially on the same level as the ridge 266.

When the bulger 264 is used it is customary 60 to substitute a presser roll 280 (Fig. 13) for the presser roll 146. The roll 280 has two high portions 282 between which there is a circumferential groove 284. The depth of the groove 284 is slightly greater than the height of the ridge 266 above 65 adjacent portions of the lateral margins 268 of the sole-engaging portion of the bulger 264, and the width of the groove is slightly greater than the width of the ridge 266 so that the high 70 portions 282 of the presser roll 280 may force the heel-seat portion of the sole effectively against the lateral portions 268 at opposite sides of the ridge 266. As the presser roll 280 advances during 75 the operation of the machine it bends the

sole transversely to a shape corresponding to the widthwise curvature of the sole-engaging portion of the bulger 264. As the knife 36 makes its cut the sole is maintained in this shape and is not permitted to be sucked away from the sole-engaging portion of the bulger by the knife.

Having described the invention, what I claim as new and desire to secure by Letters Patent of the United States is:

10. 1. A heel-seat fitting machine having, in combination, a matrix plate having a U-shaped opening defined by an edge, a pair of clamps for forcing the opposite lateral margins of the heel-seat portion of a sole against the matrix plate, a bulger having a sole-engaging face for forcing the central part of the heel-seat portion of the sole through the U-shaped opening, means for operating the clamps and the bulger, and a knife for reducing the heel-seat portion of the sole, said sole-engaging face of the bulger when in its operative position being spaced a considerable distance inward from the edge of the matrix plate to form a wide gap through which the heel-seat portion of the sole passes, said clamps being provided with extensions which when the clamps are in their operative positions project beyond adjacent portions of the sole-engaging face of the bulger and across the gap and are constructed and arranged to force portions of the sole located in the vicinity of the gap with considerable pressure through the U-shaped opening and against said edge of the matrix plate.
20. 2. A heel-seat fitting machine having, in combination, a matrix plate having a U-shaped opening defined by an edge formed by the intersection of a substantially flat face at one side of the plate with a beveled face at the other side of the plate, a pair of clamps for forcing the opposite lateral margins of the heel-seat portion of a sole against said beveled face of the matrix plate, a bulger having a sole-engaging face for forcing the central part of the heel-seat portion of the sole through the U-shaped opening and beyond said flat face of the matrix plate, means for operating the clamps and the bulger, and a knife having a cutting edge movable over said flat face of the matrix plate for reducing the heel-seat portion of the sole, said sole-engaging face of the bulger when in its operative position being spaced a considerable distance inward from said edge of the matrix plate to form a gap through which the heel-seat portion of the sole passes, said clamps being provided with extensions which when the clamps are in their operative positions project beyond adjacent portions of the sole-engaging face of the bulger and across said gap to force portions of the sole located in the vicinity of the gap with considerable pressure against said edge of the plate.
30. 3. A heel-seat fitting machine having, in combination, a matrix plate having a U-shaped opening defined by an edge, a pair of clamps for forcing the opposite lateral margins of the heel-seat portion of a sole against the matrix plate, a bulger for forcing the central part of the heel-seat portion of the sole through said opening, means for operating the clamps and the bulger, and a knife for reducing the heel-seat portion of the sole, said bulger in its operative position being spaced a considerable distance inward from said edge of the matrix plate to form a wide gap through which the heel-seat portion of the sole passes, said clamps being provided with sole-penetrating teeth which extend beyond adjacent por-

tions of the sole-engaging surface of the bulger and force portions of the sole in the vicinity of the gap through said opening and with considerable pressure against said edge of the matrix plate.

4. A heel-seat fitting machine having, in combination, a matrix plate having a U-shaped opening defined by an edge formed by the intersection of a substantially flat face at one side of the plate and a beveled face at the other side of the plate, a pair of clamps for forcing the opposite lateral margins of the heel-seat portion of a sole against the beveled face of the matrix plate, a bulger having a sole-engaging portion comprising a substantially flat central ridge extending lengthwise of the U-shaped opening, means for operating the bulger to move said ridge substantially into alignment with said flat face of the matrix plate thereby forcing the entire central part of the heel-seat portion of the sole through the U-shaped opening and beyond said face, and a knife having a cutting edge movable over said flat face of the matrix plate to reduce the heel-seat portion of the sole, the bulger being spaced a considerable distance inward from said edge of the matrix plate when said ridge is in alignment with said flat face of the matrix plate to form a wide gap through which the heel-seat portion of the sole passes, said clamps being provided with sole-penetrating teeth which project into the gap and force portions of the sole with considerable pressure against said edge of the matrix plate.

5. A heel-seat fitting machine having, in combination, a matrix plate having a U-shaped opening, a pair of clamps for forcing the lateral margins of the heel-seat portion of a sole against the matrix plate, and a bulger for forcing the central part of the heel-seat portion of the sole through said U-shaped opening, said bulger having a sole-engaging surface which is of a U-shaped outline and which is considerably smaller than said U-shaped opening and is positioned between and adjacent to said clamps, each of said clamps having teeth which extend above adjacent portions of the sole-engaging surface of the bulger when the sole is bent and clamped between the matrix plate on the one hand and the clamp and the bulger on the other hand thereby insuring that the heel-seat portion of the sole included between the bulger and the matrix plate shall be effectively forced through the U-shaped opening.

6. A heel-seat fitting machine having, in combination, a plunger unit comprising a vertically movable slide constructed and arranged to receive interchangeably one of a plurality of bulgers of different sizes, a sleeve guided by said slide and yieldingly secured thereto, horizontal lugs which are secured to the sleeve and extend considerable distances rearward of the bulger mounted upon the slide, clamps pivoted to the rear ends of said lugs and arranged at opposite sides of the bulger, and means for normally forcing the clamps against opposite sides of the bulger.

7. A heel-seat fitting machine having, in combination, a matrix plate having a U-shaped opening, means for clamping the opposite lateral margins of the heel-seat portion of an unattached sole against the matrix plate, a bulger for forcing the central part of the heel-seat portion of the sole through the U-shaped opening, a heel-seat reducing knife having a cutting edge movable forward over the matrix plate to reduce

- the heel-seat portion of the sole, and a yieldable presser roll movable forward ahead of the cutting edge of the knife for forcing the heel-seat portion of the sole against the bulger to insure 5 against the sole being sucked up by the knife, and means constructed and arranged to enable the presser roll to be moved into and away from its operative position adjacent to the knife.
3. A heel-seat fitting machine having, in combination, a plunger unit constructed and arranged to receive interchangeably one of a plurality of bulgers of different sizes, said plunger unit also comprising clamps which are positioned at opposite sides of the bulger and are mounted 10 for adjustment toward and away from each other to accommodate bulgers of different sizes, a matrix plate having a U-shaped opening, means for receiving interchangeably matrix plates having U-shaped openings of different sizes, and 15 means for moving the plunger unit to cause the clamps to force the lateral margins of the heel-seat portion of the sole against the matrix plate and then to cause the bulger to force the central part of the heel-seat portion of the sole through 20 the U-shaped opening, each of said clamps comprising a section which may be removed from the clamp to accommodate bulgers of a predetermined shape.
9. A heel-seat fitting machine having, in combination, a matrix plate having a U-shaped opening and a substantially flat face intersected by the opening, a bulger for forcing the central part of the heel-seat portion of a sole through 25 the U-shaped opening and beyond said face of the matrix plate, said bulger having a sole-engaging portion comprising a substantially flat central ridge extending lengthwise of the U-shaped opening, means for moving the bulger until said ridge is approximately in alinement with said face of the matrix plate, a knife having a substantially straight cutting edge, means for moving the knife forward with its cutting edge in engagement with said face of the matrix 30 plate to reduce the heel-seat portion of the sole, and a yieldable presser roll movable forward with and ahead of the knife, said roll having a circumferential groove which is slightly wider than said ridge of the bulger and is constructed and arranged progressively to conform the central part of the heel-seat portion of the sole to the sole-engaging portion of the bulger.
10. A heel-seat fitting machine having, in combination, a matrix plate having a U-shaped opening and a face intersected by said opening, means for clamping the lateral margins of the heel-seat portion of an unattached sole against the matrix plate, a bulger for forcing the central part of the heel-seat portion of the sole through 35 the U-shaped opening, said bulger having a sole-engaging portion comprising a substantially flat central ridge extending lengthwise of the U-shaped opening and beyond said flat face of the matrix plate, said bulger having a sole-engaging portion comprising a substantially flat central ridge extending lengthwise of the U-shaped opening and beveled lateral margins, a heel-seat reducing knife having a cutting edge movable over said flat face of the matrix plate to reduce the heel-seat portion of the sole, and a presser roll comprising a circumferential groove which is wider than said ridge of the bulger and has at its opposite sides portions of relatively large diameter which taper 40 toward the groove, said presser roll being movable forward ahead of the cutting edge of the knife for forcing the heel-seat portion of the sole against the bulger to insure against the sole being sucked up by the knife as it reduces the heel-seat portion of the sole.
11. A heel-seat fitting machine having, in combination, a matrix plate having a U-shaped opening and a substantially flat face intersected by the opening, a bulger for forcing the central part of the heel-seat portion of the sole through 45 said opening and beyond said face of the matrix plate, said bulger having a sole-engaging portion comprising a substantially flat central ridge which is parallel to said face of the matrix plate and extends lengthwise of the U-shaped opening, means for moving the bulger toward the matrix plate until said ridge is approximately in alinement with said face of the matrix plate, a knife movable forward over said face of the matrix plate to reduce the heel-seat portion of the sole, and a yieldable presser roll movable forward with and ahead of the knife, said presser roll having a circumferential groove which is slightly wider than the ridge of the bulger and also having 50 frusto-conical surfaces which are located at opposite sides of and taper toward the groove, said roll being constructed and arranged progressively to conform the central part of the heel-seat portion of the sole to the sole-engaging portion of the bulger.
12. A heel-seat fitting machine having, in combination, a matrix plate having a U-shaped opening defined by an edge formed by a substantially flat face at one side of the plate and a beveled face at the other side of the plate, means for clamping the lateral margins of the heel-seat portion of an unattached sole against the beveled face of the matrix plate, a bulger for forcing the central part of the heel-seat portion of the sole through the U-shaped opening and beyond said flat face of the matrix plate, said bulger having a sole-engaging portion comprising a substantially flat central ridge extending lengthwise of the U-shaped opening and beveled lateral margins, a heel-seat reducing knife having a cutting edge movable over said flat face of the matrix plate to reduce the heel-seat portion of the sole, and a presser roll comprising a circumferential groove which is wider than said ridge of the bulger and has at its opposite sides portions of relatively large diameter which taper 55 toward the groove, said presser roll being movable forward ahead of the cutting edge of the knife for forcing the heel-seat portion of the sole against the bulger to insure against the sole being sucked up by the knife as it reduces the heel-seat portion of the sole.
13. A heel-seat fitting machine having, in combination, a matrix plate having a U-shaped opening and a face intersected by the opening, means for interchangeably receiving one of a plurality of matrix plates having U-shaped openings of different sizes, a plunger unit comprising a pair of clamps for forcing the lateral margins of the heel-seat portion of a sole against said matrix plate and also comprising a bulger for forcing the central part of the heel-seat portion of the sole through the U-shaped opening of the matrix plate and beyond said face of said plate, said plunger unit being constructed and arranged to receive interchangeably one of a plurality of bulgers of different sizes selected in accordance with the size of the U-shaped opening of the matrix plate, the respective clamps being movable into engagement with the opposite sides of 60 bulgers of different sizes about axes which are arranged approximately at right angles to said face of the matrix plate and are located considerable distances rearward of the U-shaped opening, a knife having a cutting edge, and

means for moving the knife forward with its cutting edge in engagement with said face of the matrix plate to reduce the heel-seat portion of the sole.

- 5 14. A heel-seat fitting machine having, in combination, a matrix plate having a U-shaped opening and a face intersected by the opening, means for receiving interchangeably one of a plurality of matrix plates having U-shaped openings of 10 different sizes, a bulger, a plunger unit constructed and arranged to receive interchangeably one of a plurality of bulgers of different sizes, a pair of clamps carried by the plunger unit, means for moving the plunger unit in a predetermined path to cause the clamps to force the side margins of the heel-seat portion of the sole against the matrix plate and then to cause the bulger to force the central part of the heel-seat portion of the sole through the U-shaped opening and beyond said face of the matrix plate, a knife having a cutting edge which is in engagement with said face of the matrix plate, mechanism for moving the knife forward with its cutting edge in engagement with said face of the 25 matrix plate to reduce the heel-seat portion of the sole, said clamps being movable widthwise of the sole to accommodate bulgers of different sizes, means for normally forcing the respective clamps against opposite sides of the bulger, and 30 stops for limiting movement of the clamps toward each other when there is no bulger in the plunger unit.
- 15 15. A heel-seat fitting machine having, in combination, a matrix plate having a U-shaped opening and a flat face intersected by the opening, means for receiving interchangeably matrix plates having U-shaped openings of different sizes, a bulger, a movable slide constructed and arranged to receive interchangeably one of a plurality of bulgers of different sizes, a second slide movable with the first-named slide, a spring for normally maintaining the second-named slide in a predetermined position with relation to the first-named slide, lugs secured to and extending rearward from the second-named slide, clamps supported by and pivoted to the respective lugs, means for normally forcing said clamps

against opposite sides of the bulger, means for moving both of said slides toward the matrix plate to cause the clamps to force the margin of the heel-seat portion of a sole against the matrix plate and then to cause the bulger to force the central part of the heel-seat portion of the sole through the U-shaped opening and above said face of the matrix plate, a knife having a cutting edge, and means for moving the cutting edge of the knife over said face of the matrix plate to reduce the heel-seat portion of the sole.

16. A heel-seat fitting machine having, in combination, a matrix plate having a U-shaped opening and a face intersected by the opening, means for receiving interchangeably one of a plurality of matrix plates having U-shaped openings of different sizes, a slide movable in a predetermined path, a sleeve movable with and yieldable with relation to the slide, a pair of clamps carried by the sleeve and constructed and arranged to force the side margins of the heel-seat portion of a sole against the matrix plate, a bulger for forcing the central part of the heel-seat portion of the sole through the U-shaped opening and beyond said face of the matrix plate, said slide being constructed and arranged to receive interchangeably one of a plurality of bulgers of different sizes, said clamps being movable into engagement with bulgers of different sizes about 30 respective axes which are arranged at approximately right angles to said face of the matrix plate and are located considerable distances rearward of the matrix plate, means for moving the slide and the sleeve toward the matrix plate to 35 clamp the side margins of the heel-seat portion of the sole against the matrix plate and then to force the central part of the heel-seat portion through the U-shaped opening and beyond said face of the matrix plate, a knife having a cutting edge, and means for moving the knife forward with its cutting edge in engagement with said face of the matrix plate to reduce the heel-seat portion of the sole.

45

JOHN WILLIAM PRATT.
